INVENTOR:
Robert R. Richardson

BY *Albert Allen*

ATTORNEYS.

UNITED STATES PATENT OFFICE.

ROBERT R. RICHARDSON, OF GLENDALE, OHIO, ASSIGNOR TO THE RICHARDSON COMPANY, OF LOCKLAND, OHIO, A CORPORATION OF OHIO.

ROOF.

Application filed December 3, 1924. Serial No. 753,589.

To all whom it may concern:

Be it known that I, ROBERT R. RICHARDSON, a citizen of the United States, and a resident of Glendale, in the county of Hamilton and State of Ohio, have invented certain new and useful Improvements in Roofs, of which the following is a full, clear, and exact description, reference being had to the accompanying drawing, forming part of this specification.

My invention relates to roofs formed of composition shingles more particularly of the type formed of felt impregnated with asphalt and covered with a granular slate or other mineral.

Roofing of the composition type is quite thin, as compared to wooden shingles, tiles or slates, which have been customarily used as roof coverings, and hence give a level appearance to the roof, which to those accustomed to the other forms of roofing is lacking in attractiveness to the eye.

It is one of my objects to provide a roof of shingles laid in a particular manner in which this flatness of appearance is avoided, and a considerable thickness provided at the projecting ends of the single butts.

In forming composition shingles, covered with slate and other mineral granules, the processes employed while rapid and economical, result in the formation of many imperfect shingles, known as "seconds". These seconds are discarded or sold cheap but it is injurious to the reputation of the manufacturer to sell them, as the usual defects are those in the mineral covering, and when laid in a roof, the appearance is not perfect, and will reflect on the manufacturer who sells the roofing.

It is my object to provide in my roofs for the use of seconds, as an underlying course, thereby making a safe market for them, as they will not be visible in the roof.

It is also my object to provide a method of laying shingles, in which complete and effective coverage for the roof is provided without the use of much more roofing than is at present employed to cover a given area, and yet providing a double thickness at the butts of the shingles, as has been stated.

I accomplish my objects by that certain construction and arrangement of parts to be hereinafter more specifically pointed out and claimed.

In the drawing:

Figure 1 is a plan view of a section of roofing laid according to my invention.

Figure 2 is a section taken through such a roof, as is shown in Figure 1.

I employ regular shingles 1, and also shingles 2 which may be of the same size, and need not be coated with slate particles, or if they are, may have imperfections in the surfacing, without this being exposed in the roof.

In proceeding to lay a roof, omitting consideration of a starting strip, the first course may be formed of regular commercial size shingles 1, laid lengthwise, side by side in a course A. As indicated, the shingles can be set close to each other, without leaving the usual space of around half an inch, which is used in composition shingle work at present for the purpose of giving depth of appearance.

Next a row of the shingles 2 are laid in overlapping relation to the first course, by the shingles mounted crosswise instead of lengthwise.

This second course, indicated as course B, may be so formed that the shingles abut each other tightly, end for end. Also the lower edge of the course may be set much higher up along the first course, than is possible with full coverage, in shingles, all laid the same way.

The shingles in course B, extend beyond the upper ends of the shingles in course A. Nails may be driven through the lower ends of the shingles in course B, thereby holding down the projecting ends or butts of the shingles in course B.

The third course will be laid of shingles 1, which course, indicated as C, will have its lower ends brought into line with the lower ends or exposed lateral edges of the shingles in course B.

The fourth course D will be laid as the course B is laid, over the shingles in course C, and in this wise the roof is completed.

The usual shingle sizes are wide enough with relation to length to permit of plenty of overlap, of the shingles laid crosswise, and in each course there will be a double thickness edge along each course. The shingles laid crosswise avoid the necessity of laying shingles with a small exposure of butts, as in usual present day practice, and

there will be a very small chance of the meeting line of any lengthwise course co-inciding with the meeting line of the crosswise course beneath it.

5 The possibility of greater exposure of the shingles 1 in the particular example of my invention illustrated, compensates to a large degree for the shingles 2 being entirely covered up in the laying of the roof.

10 Instead of using seconds for the concealed courses, or using unslated composition shingles, it will be highly practical to use shingles formed of macerated roofing scraps and imperfect shingles, made into slab form by 15 extrusion through a nozzle.

In my new form of roof, it will be possible to lay the shingles like tile, in courses which are not staggered but which are laid so as to form rows lengthwise and crosswise 20 of the roof. The butting of the shingles laid in the concealed courses will close the roof tightly, but in case the dividing line between shingles in two courses coincides, then the roofer will cut away the shingles 25 of the underlying course as it is being laid, enough to prevent coincidence. Of course the usual staggered relation may be maintained.

Having thus described my invention, what 30 I claim as new and desire to secure by Letters Patent, is:—

35 1. A roof formed of composition shingles of substantially uniform thickness laid in courses, said shingles having greater length in one direction than the other, and the courses formed by rows of shingles set lengthwise of the slope of the roof, alter-

nating with rows set crosswise of the slope of the roof, with the lower edges of the rows set lengthwise, co-inciding with the lower 40 edges of the rows set crosswise, and the rows set crosswise overlapping the upper ends of the rows set lengthwise.

2. A roof formed of composition shingles of substantially uniform thickness laid in 45 courses, said shingles having greater length in one direction than the other, and the courses formed by rows of shingles set lengthwise of the slope of the roof, alternating with rows set crosswise of the slope of 50 the roof, with the lower edges of the rows set lengthwise, coinciding with the lower edges of the rows set crosswise, and the rows set crosswise overlapping the upper ends of 55 the rows set lengthwise, with the shingles of the rows set crosswise, butted against each other in the courses.

3. A roof formed of composition shingles of substantially uniform thickness laid in 60 courses, said shingles having greater length in one direction than the other, and the courses formed by rows of shingles set lengthwise of the slope of the roof, alternating with rows set crosswise of the slope of 65 the roof, with the lower edges of the rows set lengthwise, coinciding with the lower edges of the rows set crosswise, and the rows set crosswise overlapping the upper ends of the rows set lengthwise, with the rows of shingles set lengthwise laid so as to form 70 rows up and down as well as crosswise of the roof.

ROBERT R. RICHARDSON.
